ACCORDION CONSTRUCTION

Carl Lindeberg, De Kalb, Ill., assignor to The Rudolph Wurlitzer Company, Cincinnati, Ohio, a corporation

Application March 9, 1939, Serial No. 260,668

7 Claims. (Cl. 84—376)

This invention relates to the construction of an accordion, particularly in respect to the arrangement of the bass reed blocks, and their relative position with respect to the treble reed blocks, primarily to permit of reduction in its overall size to provide a more compact instrument.

It is the common practice to mount the bass reed blocks upon the bass valve board so that they extend substantially vertically therefrom into the space surrounded by the bellows, while the treble reed blocks extend downwardly to said space but not into it so that when the bellows are collapsed, there will be no interference between the bass and treble blocks. This requires substantial space in the treble box to accommodate the treble blocks.

This invention resides in the construction and arrangement of the bass reed blocks and their relative position to the treble reed blocks for permitting the latter to extend well into the bellows section, resulting in a more compact instrument capable of more graceful lines due to the shallowness which may be obtained in the treble box and gallery.

The principal feature of the invention resides in the mounting and arrangement of the bass reed blocks in respect to the bass valve board in such manner as will take up the minimum of space in the bellows section, and clear the treble reed blocks so as not to interfere therewith. This is accomplished by arranging the larger of the bass blocks substantially parallel with the board and the other blocks at an angle thereto, and with respect to each other. Such arrangement will reduce the overall space required therefor and will permit the treble reed blocks to extend a substantial distance into the bellows section when collapsed.

The full nature of the invention will be understood from the accompanying drawing and the following description and claims:

Fig. 1 is a horizontal section through the accordion with parts removed and illustrating the relative positions of the reed blocks. Fig. 2 is a plan view of a portion of the bass valve board showing the required valves associated therewith. Fig. 3 is a section taken on the line 3—3 of Fig. 1.

In the drawing there is illustrated a section of an accordion comprising a treble box 10 over which a gallery 11 extends, terminating in the usual key bed 12 having the treble keys 13 mounted thereon. Secured to the treble box 10 there is a bellows section 14 provided with the usual bellows 15. A bass box 16 is secured to the op-

posite side of the bellows section from the treble box and has mounted therein a valve board 17 separating the reed compartment or wind chest 18 from the valve compartment 19.

For purposes of illustration, the valve compartment is shown with the usual bass valve operating buttons 20 extending through apertures formed in one wall thereof, which are adapted to be connected in the usual manner, not shown, with the valve operating rods 21 and 10 22. Inasmuch as the valve control mechanism is well known in the art and forms no part of this invention, it is eliminated from the drawing. The valve board 17 is provided with the usual ports 23 and 24 controlled by the valves 25 and 15 26, respectively, which in turn are actuated through the usual arms 27 by the rods 21 and 22, said valves being normally maintained in closed position by the springs 28.

In the treble box there is provided a treble 20 valve board 29 having ports 30 communicating with the chambers of the respective treble reed blocks 31 depending therefrom and extending well into the bellows compartment. The ports 30 are controlled by the usual valves, not shown, 25 which in turn are actuated by the keys 13.

Mounted upon the bass valve board 17 there is a pair of companion bass reed blocks 32 and 33 connected in common with the ports 24 controlled by valves 26. A similar pair of tenor 30 reed blocks 34 and 35 are associated together and connected in common with the ports 23 controlled by the valves 25.

The bass reed block 32 lines horizontally upon and extends substantially parallel with the valve 35 board 17. One side wall of the reed block comprises the valve board, and the closed end thereof lies adjacent the side wall of the box 16. The upper side of the reed block is provided with the usual slots indicated at 36 over which the reeds 40 37 are mounted. The companion bass block 33 is supported adjacent block 32 so as to be in communication therewith and their common ports 24, and extends at an angle thereto slightly into the bellows section. This block is positioned at 45 such an angle as not to interfere with the reeds of the block 32 and at the same time avoid interfering with the downwardly extending treble reed block 31. It likewise is provided with the usual slots 36 and reeds 37.

Thus, the two companion bass blocks 32 and 33 are jointly controlled by the valves 26, but are so arranged as not to interfere with the downward projection of the treble reed blocks.

The tenor reed blocks 34 and 35, being shorter 55

than the bass blocks, are set at only a slight angle, since they are not long enough to interfere with the downward projection of the treble block 31. However, they are arranged at a slight angle 5 to avoid interference between the reeds of adjacent blocks 33 and 34, and are jointly controlled by the valves 25 through the common ports 23.

From the foregoing it will be noted that the longer of the bass reed blocks is disposed laterally so as not to extend into the bellows section, while the shorter thereof is mounted at an angle to avoid interference with the treble blocks, both associated bass blocks being controlled by common valves. Thus, the treble blocks are permitted to extend a substantial distance within the bellows section, which results in a reduction in width of the treble box. This permits of a more compact instrument with a shallow gallery of improved appearance.

20 The invention claimed is:

1. In an accordion, a valve board having a series of valve controlled ports therein, a reed block mounted upon and having one wall thereof comprising said valve board, a reed carrying wall 25 spaced therefrom and provided with a series of slots, a series of reeds associated with said slots, and a plurality of partitions extending between said valve board and reed carrying wall to form separate air chambers, each of said chambers 30 being in communication with one of said ports.

2. In an accordion, a wind chest having a valve board provided with a series of valve controlled ports, a reed block comprising a corresponding series of air chambers communicating with said 35 ports respectively, one wall of said reed block comprising said valve board, an opposite slotted wall supported in spaced relation and extending substantially parallel thereto, and a series of reeds supported by said last-mentioned wall in 40 operative association with said slots.

3. In an accordion, a box having a ported valve board mounted therein for separating said box into a wind chest on one side of said board and a valve chamber on the other side thereof, a 45 series of valves in said valve chamber for controlling said ports, a double reed block mounted on the other side of said board provided with air chambers in common communication with said ports and extending into said wind chest, 50 said double reed block having one series of chambers extending substantially parallel with said valve board and with said board forming one wall thereof, a second set of chambers having their confining walls extending at an angle to said 55 valve board, and a series of reeds associated with the respective chambers, said second set of chambers extending at such an angle with respect to the first set of chambers as to freely permit vibration of said reeds and the passage of air 60 thereby.

4. In an accordion, a box having a ported valve board mounted therein for separating said box into a wind chest and a valve chamber, a series 65 of valves associated with said board in said valve chamber for controlling said ports, a double reed block mounted on the other side of said board and having a series of air chambers in common communication with said ports and extending into said wind chest, said double reed block being 70 V-shaped in cross section, one of said blocks ex-

tending substantially parallel with the valve board, which board comprises one wall thereof and the other block extending at an angle to the first block and to said valve board, and a series of reeds mounted on one wall of each of said blocks in operative association with their respective air chambers and communicating ports respectively, the reeds of the first-mentioned block being mounted on the wall thereof toward the second-mentioned block with the adjacent wall 10 of the second-mentioned block spaced from said reeds to permit freedom of action and air flow thereby.

5. In an accordion, a wind chest comprising a bellows section, a treble box section and a bass box section, a plurality of treble reed blocks extending from said treble box section a substantial distance into said bellows section when the bellows thereof are collapsed, a bass valve board in the bass box section having a series of valve 20 controlled ports therein, a double bass reed block mounted on said board and extending into the wind chest toward the treble blocks, said respective bass reed blocks having a series of air chambers with the corresponding chambers in communication with each other and with one of said ports, one of said blocks extending substantially parallel with the valve board with said board comprising one wall thereof, the other reed block 25 extending at an angle thereto into said bellows 30 section to one side of the treble block, a series of reeds mounted on the opposite wall of the first-mentioned block from the valve board, and a series of reeds on the far side wall of the second-mentioned block. 35

6. In an accordion, a wind chest comprising a bellows section, a treble box section and a bass box section, a plurality of treble reed blocks extending from said treble box section a substantial distance into said bellows section when the 40 bellows thereof are collapsed, a bass valve board in the bass box section having a series of valve controlled ports therein, and bass reed blocks mounted on said board at an angle thereto and angularly extending toward the wind chest and 45 treble blocks, one of said treble and bass blocks having overlapping ends when the bellows are collapsed and arranged at such relative angles as to extend to one side of each other so as to avoid interference therebetween and permit both 50 sets of blocks to be encompassed in a minimum of space.

7. In an accordion, a wind chest comprising a bellows section, a treble box section and a bass box section, a plurality of treble reed blocks extending from said treble box section a substantial distance into said bellows section when the bellows thereof are collapsed, a bass valve board in the bass box section having a series of valve 60 controlled ports therein, and a plurality of double bass reed blocks mounted on said board and extending into the wind chest toward the treble blocks, said reed blocks extending at an angle to each other and at least one thereof overlapping one of the treble reed blocks and extending angularly to one side thereof to permit nesting of the treble and bass reed blocks so as to avoid interference with each other in a minimum of space 65 when the bellows are collapsed.

CARL LINDEBERG. 70
